United States Patent Office

Des. 223,307
Patented Apr. 4, 1972

223,307

FOUNTAIN PEN

Geoffrey Nockolds, Spencer Cottage,
Upham, Hampshire, England

Filed July 31, 1970, Ser. No. 24,243

Claims priority, application Great Britain Feb. 2, 1970

Term of patent 14 years

Int. Cl. D19—06

U.S. Cl. D74—17

FIG. 1 is a front elevation of a fountain pen showing my new design;

FIG. 2 is a side elevation thereof;

FIG. 3 is a top plan;

FIG. 4 is a bottom plan thereof; and

FIG. 5 is a front perspective thereof as it appears with the cap removed from the pen.

The feed bar on the underside of the writing point nib is conventional in appearance.

I claim:

The ornamental design for a fountain pen, as shown and described.
